FOLDABLE TABLE OR LIKE ARTICLE

Arthur Marx, Forest Hills, N. Y.

Application February 11, 1948, Serial No. 144,424

Term of patent 3½ years

(Cl. D33—14)

To all whom it may concern:

Be it known that I, Arthur Marx, a citizen of no country, residing at Forest Hills, county of Queens, State of New York, have invented a new, original, and ornamental Design for a Foldable Table or Like Article, of which the following is a specification, reference being had to the accompanying drawing, forming part thereof.

In the drawing:

Figure 1 is a front view of a foldable table or like article, with the drop leaf and its supporting board in folded condition and showing my new design;

Figure 2 is an edge view of said table or like article in the same condition;

Figure 3 is a perspective front view of said foldable table or like article with the drop leaf in raised and its supporting board in extended position;

Figure 4 is a side view of the table or like article in the condition shown in Figure 3.

I claim:

The ornamental design for a foldable table or like article, substantially as shown and described.

ARTHUR MARX.
